UNITED STATES PATENT OFFICE.

JOHN HENRY WALKER, OF LEXINGTON, KENTUCKY.

COMBINATION-TOOL.

1,313,432.

Specification of Letters Patent.

Patented Aug. 19, 1919.

Application filed April 17, 1917. Serial No. 162,603.

To all whom it may concern:

Be it known that I, JOHN H. WALKER, a citizen of the United States, and a resident of Lexington, in the county of Fayette and 5 State of Kentucky, have invented a certain new and useful Improvement in Combination-Tools, of which the following is a specification.

This invention is an improvement on the 10 combination tool disclosed in the Patent 1,135,743, issued to me on April 13, 1915.

One of the principal objects of the invention is to provide a spirit level attachment 15 operating as a spirit level both on and off of the stock or handle of the device, and also operating in conjunction with the stock in rapidly adjusting the blades of the tool to predetermined angular positions.

Another object of the invention is to provide the stock or handle with notches or shoulders arranged at such positions on the stock as to determine, when engaged by one 20 of the blades, the more commonly used angular positions of the blade, the purpose being to allow quick and accurate adjustment of the blade to the more commonly 25 used angles.

A further object of my present invention is to improve generally the utility of the 30 combination tool.

With these and other objects in view which will become apparent as the description proceeds, the invention resides in the construction, combination, and arrangement 35 of parts hereinafter more fully described and claimed, and illustrated in the accompanying drawings in which like characters of reference indicate like parts throughout the several figures, of which—

40 Figure 1 represents an elevational view of the tool looking at the same from one end of the stock or handle;

Fig. 2 represents a side elevational view of the tool;

45 Fig. 3 represents a view in edge elevation, taken partially in section on the plane indicated by the line 3—3 of Fig. 2;

Fig. 4 represents a horizontal sectional view taken on the plane indicated by the line 50 4—4 of Fig. 2, looking in the direction indicated by the arrows;

Fig. 5 represents a plan view of the tool

when the arms are moved into alinement to form a straight edge, the stock being formed into parallel relation with the blade;

55

Fig. 6 represents an elevational view showing the application of the level attachment in securing correct angular adjustment for one of the arms;

Fig. 7 is a similar view showing the reverse side of the tool;

Fig. 8 represents a view in section taken horizontally on the plane indicated by the line 8—8 of Fig. 7;

Fig. 9 represents an elevational view of 65 the tool showing the use of the same as an outside caliper.

In the improved construction of the tool the stock or handle 5 is made of two strips or lengths of metal of suitable weight, between which at one end is arranged a spacer block 6, and between the other ends of which the inner ends of the blades 7 and 8 respectively are pivoted.

The inner ends of the blades are provided 75 at analogous corners with rounded ears 9, which ears are offset from the blades in opposite directions whereby the blades themselves lie in coplaner relation, as shown clearly in Fig. 1. Between the ears is interposed a hardened washer 10. These ears are pivoted on the rivet 4 which securely binds the parts together in such manner that they will remain in adjusted position through frictional engagement of one part 80 with the other.

In the patented tool above referred to, the blades are limited to a maximum adjustment of 90° with relation to the stock or handle.

In the improved tool the blade 8, termed the 90 right hand blade, similarly is limited to a maximum adjustment of 90° with regard to the handle or stock 5, but the blade 7, termed the left hand blade, is not so limited but

may swing through an arc of 180° with regard to the handle or, in other words, may be moved as shown in Fig. 5, into axial alinement with the stock or handle. The

blades 7 and 8 are so mounted that, when they are brought into alinement one with 95 the other, their inner ends will abut against each other, as clearly shown. When these

blades are moved into alinement they form 100 a continuous straight edge. The blade 8, in

order to be limited in its movement, is equipped at its inner end with a lug 11 which moves through an arcuate recessed portion 12 provided at the inner end of one 5 of the plates forming the stock or handle, such recess 12 defining square shoulders 13 and 14 respectively, which lie at right angles to each other and with which the lug 11 is adapted to coöperate in limiting the movement 10 of the blade 8. The shoulder 13 lies in the medial line of the stock and limits the maximum swing of the blade to a position at 90° relative to the stock. The shoulder 14 will limit the inward movement of the 15 blade 8 toward the stock or handle, when the outer edge of the blade lies in parallel relation with the longitudinal edges of the stock. The outer edges of the blades 7 and 8 are graduated on both sides to form a rule, 20 as in the original construction.

The front face of the stock or handle is graduated, as shown in Fig. 2, at 15, and these graduations coöperate with the inner edges of the arms 7 and 8 in determining 25 the angles at which these arms are arranged relative to the stock or handle 5. Thus, in Fig. 2, the blade 8 lies at an angle of 30° with the stock 5, as determined by the fact that the inner edge of the blade intersects the adjacent longitudinal edge of the handle 30 at the point where the graduation "30" occurs.

In order that quick and accurate adjustments of the blade 8 into its various angular 35 positions may be had, the inner surface of one of the plates or strips forming the stock or handle, is provided with notches as indicated at 16 in Fig. 3, which notches define shoulders coinciding with the graduations 40 15 on the front face of the stock. Thus, to quickly adjust the blade 8, say at an angle of 20° with respect to the stock, the blade will be grasped and slightly twisted and moved toward the 20° mark, until the 45 inner edge of the blade abuts with the shoulder coinciding with the graduation "20." The blade will then be at an angular position of 20° with respect to the stock or handle. The blade, as well as the stock 50 or handle, is made of suitable metal, and it is necessary only to slightly twist the blade 8 in order to bring its inner edge into position to engage with the shoulders defined by the notches 16. As soon as the blade is 55 released it will straighten out in position to be readily adjusted without engagement with the shoulders, but it will remain at its predetermined angular position relatively to the stock until the blade is forcibly moved.

The graduations 15 are arranged at intervals of 5° , and in order to provide for adjustments of the blade 8 at intermediate

points, the front face of the blade at the lower end of the latter is graduated as indicated at 17 into degree and fractional degree spaces, as clearly shown. For the sake of illustration presume it is desired to lay off an angle of thirty-two degrees upon a 65 surface. The blade is first adjusted to a thirty degree score upon the stock as shown in Fig. 2 and a suitable mark made upon the surface. The second degree score of the graduations 17 is then moved to coincide with this mark and in this position the blade will 70 determine an angle of thirty-two degrees. 75

The left hand blade 7 also operates in securing the correct angular value of any given obtuse angle, by adjusting the blade with relation to the stock or handle, to coincide with the angle to be measured, and then bringing the right hand blade into position to abut the left hand blade, and then determining the angular relation of the right hand blade with respect to the stock 85 or handle. The correct angular measurement of the obtuse angle will be determined by subtracting from 180° the value of the angle between the blade 8 and the handle. If, the blade 8 abuts against the blade 7, 90 and lies let us say at 15° with regard to the stock, the obtuse angle between the blade 7 and the stock, and hence the obtuse angle with which it coincides, will be a 165° angle.

I have provided a level attachment for 95 use in conjunction with the tool, and this attachment includes a body 18 projecting from one edge of which are the flanges 19 defining a groove or channel whereby the level attachment may be slidably mounted 100 upon the stock 5 of the tool, as shown in Figs. 6 and 7. On its opposite edge from the flanges 19, the attachment is equipped with a level vial 20, constructed as usual. The upper end of the body 18 is provided 105 with a lug or stop 21 against which the inner edge of one blade or the other is to be brought in determining the angular relation of such blade with respect to the stock.

As shown in Fig. 6, the reverse or rear 110 face of the stock is provided with two sets of graduations 23 and 24 respectively, which are arranged in reverse order with respect to each other, and with which the level attachment is adapted to coöperate in 115 determining the adjustment of the blades 8 and 7 into angular relations with regard to the stock and with regard to a line at right angles to the stock respectively. Thus, in Fig. 6, the attachment is so positioned 120 that its upper edge coincides with the graduation "25" of the series 23. The blade 8 is then brought down so that its lower edge engages with the lug 21. The blade will 125 then be at an angle of 25° with regard to the stock 5. Thus, adjustments of the level

attachment at any of the graduations 23, will determine various angular positions of the blade 8 relatively to the stock. While the level attachment is positioned upon the stock, it may be utilized as a level by bringing the blade, opposite the one with which the leveling attachment is coöperating, in determining an angular adjustment, into closed position relatively to the handle or stock, and then laying the tool with the edge of the closed blade against the surface to be leveled, as will be readily understood.

The graduations 24 are to determine the position of the leveling attachment in adjusting the blade 7 at various angular positions relatively to a line drawn at right angles to the stock through the pivot 4. Thus, if the level attachment is placed on the stock on the opposite edge from that shown in Fig. 6, and moved let us say, until the upper edge of the level attachment coincides with the graduations "50" of the series 24, the blade 7 when brought so that its lower edge engaged against the lug 21, would lie at an angle of 50° with respect to a line drawn at right angles to the stock through the pivot 4 and on the same side of the stock as the blade 7.

The level attachment is equipped, for convenience, with a detachable scratch awl which may be utilized in connection with the tool in laying off work.

The outer or free ends of the blades 8 and 7 extend beyond the outer end of the stock 5, and are so shaped as to provide points or fingers 25, which are adapted to be utilized as outside calipers, as indicated in Fig. 9.

When the level attachment is used in determining the various angular adjustments of the blades, it may, if desired, be removed and the blades will remain in adjusted positions until forcibly moved into other adjustments.

The improved tool has been found to be of great utility, serving not only the specific uses set out, but others too numerous to mention, and which are obvious.

It may be stated that the flanges 19 will of course frictionally engage the stock or handle with such force as to retain the level attachment in adjusted position upon the stock against accidental displacement. The floor of the channel defined by the flanges 19 is smooth and straight, so as to lie flat against the lateral edges of the stock. The scratch awl is detachably positioned in openings provided in the wall of the level attachment, so that when the scratch awl is in position on the attachment, it extends above the vial 20, whereby to protect the latter.

I claim:

1. A tool including a stock comprising

spaced plates, a blade pivoted between the plates, graduations arranged transversely on the outer surface of one of the plates to determine various angular relations of the blade relatively to the stock, said one plate having its inner surface provided with a plurality of shoulders arranged in coincidence with the graduations and against which shoulders the blade can be selectively brought for quickly and positively determining various angular positions of the blade relatively to the said stock. 65

2. A tool including a stock, a blade pivoted thereon, said blade being relatively flexible, notches provided on the stock at various intervals to be engaged by the blade for determining various angular relations 80 of the blade relatively to the stock, and graduations provided on the stock for identifying the angles determined by the notches.

3. A tool comprising a stock, a pair of 85 blades coöperating with said stock and ears formed on homologous corners of said blades pivoted to the stock and offset whereby the blades lie in the same plane and the adjacent ends of the blades can abut each 90 other to limit the adjustment of the blades relative to the stock.

4. A tool including a stock, a blade pivoted thereon, graduations on the stock with which the blade is adapted to coöperate in 95 positioning the blade at various predetermined angular relations with the stock, and degree graduations provided on the outer end of the blade for determining the angular relations of the blade relatively to the 100 stock intermediate the angular positions determined by the graduations on the stock.

5. The combination with a tool including a stock and a blade pivoted thereon, of an attachment including a body slidable longitudinally of the stock and having a lug against which the blade may engage for determining the correct angular positions of the blade relatively to the stock, said stock being provided with graduations with which 110 the attachment is to coöperate in determining various angular positions of the blade. 105

6. The combination with a tool including a stock and a blade adjustable into various angular positions relative to the stock, of an attachment slidable longitudinally on the stock and against which the blade is to be engaged in determining angular relations of the blade relatively to the stock, said attachment being provided with a leveling vial 120 whereby the stock may be leveled simultaneously with the adjustment of the blade into the desired angular position. 115

7. A tool consisting of a stock comprising spaced plates, one of said plates being 125 provided at one end thereof with an arcu-

ate recessed portion, a pair of blades arranged between the plates, a lug formed on one of said blades coöoperating with the recessed portion of said plate for limiting the adjustment of said blade relative to the stock and ears formed on homologous cor-

ners of each of said blades and offset whereby the blades lie in the same plane and the adjacent ends of the blades abut each other when the blades are brought in alinement 10 one with the other.

JOHN HENRY WALKER.
